UNITED STATES PATENT OFFICE.

WILLIAM NOBLE BARRETT, OF MEADVILLE, PENNSYLVANIA.

CORKSCREW.

SPECIFICATION forming part of Letters Patent No. 388,945, dated September 4, 1888.

Application filed November 12, 1887. Serial No. 254 990. (No model.)

To all whom it may concern:

Be it known that I, WILLIAM NOBLE BARRETT, a citizen of the United States, residing at Meadville, in the county of Crawford and State 5 of Pennsylvania, have invented certain new and useful Improvements in Corkscrews; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 The special object of the invention is to improve that class of corkscrews which are operated by a lever.

Figure 1 of the drawings is an elevation in perspective; Fig. 2, a side elevation with the case and nuts in vertical section; Fig. 3, a perspective detail view of the slide-nut; Fig. 4, a similar view of the drive nut with its rack.

In the drawings, A represents the case-support with the flat base a, having screw-holes 25 a' a', so that it may be attached to a table, shelf, or bracket. At one side of the front end of this support is the circular rack a², while on the arm c¹ of case C is formed a corresponding rack, c². Through the middle of 30 these racks passes a pivot, B, so that the case C may be set at any desired angle to its support A. The case C is slotted at c³, and in this slot travels a screw, d, on the slide-nut D, so that the latter may move up and down for the 35 length of the slot.

E E' are two screws, having, respectively, right and left threads, separated by the piece e. On the screw E works a drive-nut, F, with a corresponding thread and with the outside 40 rack, f. In the latter works, through the case-

slot c⁴, the toothed sector g, which is made integral with or fast to the end of the hand-lever G. This lever is fulcrumed on a pivot, g', in the case-arms a³ a³. When the lever G is lifted, the nuts and screws move down with the 45 rack until the screw d reaches the bottom wall of the case-slot c³. The screw E then bites upon the cork, and as the lever continues to rise works into the cork, while the screw E' revolves and the nut F moves down upon it as 50 well as with it, the pitch of the thread upon the screw E being much greater than upon the screw E', so that the motion of the screw E' and nut F gives a downward movement or feed to the screw E. This feed continues until the 55 lever's sector has ceased to actuate the rack.

In order to draw the cork out of the bottle, a downward pressure is given to the lever, and this lifts the rack, screws, and nuts until the screw d reaches the upper wall of its slot c³, 60 when the cork will have been drawn out. By a continued movement of the hand-lever the screw E works out of the cork and the operation is completed.

Having thus described all that is necessary 65 to a full understanding of my invention, what I claim as new, and desire to protect by Letters Patent, is--

The combination, with the case C, slotted at c³ c⁴ and the nut D, carrying screw d in slot c³, 70 of the right and left screws E E' on the same stem, the drive-nut F, having outside rack, f, and the toothed sector on lever G, whereby a corkscrew may be operated in the manner and for the purpose set forth.

WILLIAM NOBLE BARRETT.
